UNITED STATES PATENT OFFICE

2,590,754

DEAERATING APPARATUS

Edwin L. Cline, Pasadena, Calif., assignor to Clayton Manufacturing Company, Alhambra, Calif., a corporation of California

Original application August 30, 1943, Serial No. 500,591. Divided and this application October 26, 1945, Serial No. 624,892

10 Claims. (Cl. 183—2.5)

1

The present invention relates to liquid and gas separation apparatus and more particularly to deaerating apparatus for use in separating the air from the liquid of a hydraulic dynamometer apparatus, as set forth in my copending application Serial No. 500,591, filed August 30, 1943, entitled Hydraulic Dynamometer, and of which the instant application is a true division.

The principal object of the invention is to provide means for effectively separating air from a liquid.

Another object of the invention is to provide a device for separating air and liquid by centrifugal force arranged in such fashion that the path of flow of the liquid is "straightened out" before it leaves the device so that no air is entrained in the discharged liquid.

Another object of the invention is to provide liquid and gas separation apparatus including means for preventing the gas containing liquid from passing directly from the inlet to the outlet of said apparatus.

Still another object of the invention is to provide a centrifugal gas and liquid separator including means for controlling the depth of the vortex of the rotating liquid.

Other objects and advantages of the invention will be apparent from the following description taken in conjunction with the accompanying drawings, in which:

Fig. 1 is an elevational view of a liquid and gas separation device embodying the principles of the present invention;

Fig. 2 is a longitudinal sectional view through the device shown in Fig. 1;

Fig. 3 is a plan view of the device shown in Fig. 1;

Fig. 4 is a horizontal sectional view taken on the line 4—4 of Fig. 2 and particularly illustrating the shape of the inlet opening of the device;

Fig. 5 is a sectional view taken on the line 5—5 of Fig. 2 and illustrating the manner in which baffle means is employed to prevent the liquid from passing directly toward the outlet of the device; and

Fig. 6 is a sectional view taken on the line 6—6 of Fig. 2 particularly showing the arrangement of the vanes in the lower section of the device for converting the whirling movement of the liquid in the device into downward substantially straight line movement.

Referring now to the drawings, the deaerating device comprises a housing consisting of an upper cylindrical section 300 and a cup-like lower section 301. A cap 302 forms a closure for the

2

upper end of the upper section 300. The lower section 301 has an upwardly projecting flange 303 (Fig. 2) on the rim thereof which is received in a mating recess 304 in the lower end of the section 300, whereby the flange and recess cooperate to maintain the sections 300 and 301 in vertical alignment.

The lower section 301 has a solid axial core 305 which is provided at its upper end with a threaded aperture 306. A plurality of radial vanes 307 extend outwardly from the core 305 and merge with the inner periphery of the section 301. The vanes 307 terminate short of the bottom of the cup section 301 as indicated at 308. The vanes 307 also terminate short of the flange 303 and a circular baffle plate 309, slightly smaller in diameter than the internal diameter of the section 301, rests flush upon the upper edges of said vanes. A wall portion 310 of the section 301 is thickened to form a pad that extends radially inwardly a sufficient distance to partially underlie the baffle 309, as is best shown in Figure 5. The thickened wall portion 310 is provided with an outlet opening 311 into which a pipe nipple 312 is threaded. A liquid discharge hose section 253 has one end thereof connected with the nipple 312 and its opposite end is connected with any suitable apparatus such as a heat exchanger, etc. (not shown).

30 The deaerator sections 300 and 301 and the cap 302 are maintained in assembled relation by a rod 315, the lower end of which extends through the baffle 309 and is threaded into the recess 306 in the core 305, as shown in Fig. 2. The upper end of the rod 315 extends through the cover 302 and a nut 316 is threaded thereon and tightly clamps the parts together. A gasket 317 under the nut 316 prevents leakage along the rod 315.

35 The upper section 300 is provided with an inlet duct 318 formed exteriorly thereof. The inlet duct 318 has a threaded circular opening 319 into which a pipe nipple 320 is threaded. An inlet hose section 155 is suitably connected with the nipple 320. Except for the circular opening 319, the inlet duct 318 is substantially rectangular in

40 cross-section and progressively decreases in width and increases in height in a direction away from the inlet opening 319. The progressive change in the width and height of the duct 318 is such that 45 the radial cross-sectional area throughout the length of the duct remains substantially the same. The duct 318 follows the general curvature of the cylindrical section 300 and merges into the interior of said section on a tangent with the 50 interior surface of said section, as is best shown 55

in Fig. 4. Hence, the liquid which passes through the duct 318 is introduced into the section 300 with a rapid rotating or whirling motion. The effect of this is to cause the liquid to tend to move radially outwardly by centrifugal force, thereby effecting a separation of the air from the liquid, in a manner readily understood. The rapid whirling motion imparted to the liquid produces a vortex, generally indicated by the dot-and-dash lines 321 (Fig. 2), and the separated air collects within this vortex. A washer or splash plate 322 is welded or otherwise secured to the rod 315 adjacent the cover plate 302. The upper end of the rod 315 is provided with a longitudinal passageway 323, which communicates with the interior of the section 301 through a plurality of vent openings 324 disposed between the washer 322 and the inner face of the cover 302. The passageway 323 and the vent openings 324 provide a means of escape for the air separated from the liquid in the deaerator. The washer or splash plate 322 prevents the liquid from being splashed up into the vent openings 324 so that the amount of liquid withdrawn from the deaerator with the air is maintained at a minimum.

A conventional coupling fitting 325 is threaded into the upper end of the tube 315 providing the passageway 323 and an air discharge tube 157 is connected to said fitting.

The periphery of the baffle plate 309 (see Fig. 5) is spaced from the inner wall of the section 301 to provide three arcuate passageways 314 which permit liquid to pass from the section 300 downwardly into the section 301 between the vanes 307. However, in view of the fact that the baffle 309 overlaps the wall portion 310, it is impossible for the liquid to pass from the section 301 directly downwardly and out through the opening 311. Instead, the liquid must pass downwardly through the recesses 314 and along the vanes 307, which have a "straightening" effect on the swirling liquid, and then pass beneath the lower edges 308 of said vanes and then into the space adjacent the thickened wall 310 communicating with the outlet opening 311.

The depth of the air vortex 321 in the deaerator is controlled so that its apex does not extend deeply enough to allow some of the air to pass out of said deaerator with the liquid discharging through the hose 253. Thus, the depth of the air vortex 321 may be controlled by making the air tube 157 of a given predetermined internal diameter so that the air will be withdrawn at a desired rate. In other words, the internal diameter of the tube 157 may be made such as to constrict the rate of flow of air therethrough so that a sufficient air pressure above atmospheric pressure is maintained within the upper housing section 300 to assure the air vortex 321 of a desired depth. As an alternative means of controlling the depth of the air vortex 321, the vent openings or orifices 324 in the rod 315 may be made such that their combined cross-sectional areas will create the necessary restriction of the air discharging from the deaerator to such rate as to give the desired depth to the vortex. Unless this depth is controlled by proper air discharge restrictions, an excess of air in the deaerator will cause air to pass into the outlet hose 253, or if the air pressure is too low the upper housing section 300 will tend to fill up with liquid and too much liquid will be withdrawn through the tube 157 with the discharged air.

The radial vanes 307 in the lower section 301 of the deaerator, in cooperation with the baffle

309, also serve to prevent the air vortex 321 from being drawn downwardly by the velocity of the liquid to such extent as to permit air to pass to the outlet hose 253. Thus, it will be apparent that the baffle 309 restricts and permits downflow only at the peripheral spaces 314 and the "straightening" action of the vanes 307 compels the swirling liquid to move downwardly, instead of rotatively, and thereby assists in maintaining an air vortex of the desired depth by further retarding liquid flow.

It will be understood that the liquid is introduced into the deaerator under substantial pressure and is whirled therein at a high velocity. This velocity is sufficient to cause the liquid and air to become separated and the liquid in the lower section 301 of the deaerator to be forced into the outlet hose section 253. The pressure of the air in the vortex 321 must, of course, be sufficiently high to insure that the liquid will be forced into the outlet hose section 253, otherwise the deaerator could not perform its intended function of air and liquid separation. The separated air is, of course, removed from the deaerator through the air tube 157.

It will also be understood that various changes may be made in the arrangement and details of construction of the liquid and gas separation device disclosed herein, without departing from the principles of the invention or the scope of the annexed claims.

It will be further understood that the liquid and gas separation device disclosed herein is of general utility and is not limited to use with a hydraulic brake unit, although the same has been found to be highly satisfactory for such specific use.

I claim:

1. A deaerating device comprising an upper cylindrical section; a lower cup-like section; a cap forming a closure for the upper end of said cylindrical section, said upper cylindrical section having an inlet duct discharging tangentially into the interior of said section, whereby liquid introduced through said inlet duct has a rapid whirling motion imparted thereto to remove the air therefrom, said lower cup-like section having an axial core and a plurality of radial vanes extending outwardly from said core and merging with the inner surface of the side wall of said lower cup-like section, said radial vanes terminating short of the bottom of said lower cup-like section; a circular baffle plate resting upon said core and the upper edges of said radial vanes, said baffle plate being smaller in diameter than the internal diameter of said lower cup-like section, whereby to provide arcuate passageways for liquid between said upper and lower sections; a portion of the side wall of said lower cup-like section being thickened and projecting inwardly to a point underlying said circular baffle plate, an outlet opening extending through said thickened wall portion, whereby liquid is prevented from passing directly from said upper cylindrical section to said outlet opening; a rod extending through said cap and having a reduced end extending through said circular baffle plate and threaded into said axial core of said lower section, the upper end of said rod projecting through said cap member and being externally threaded; a nut threaded upon said projecting end of said rod and clamping said upper and lower sections and said cap member together, a plurality of vent openings in said rod communicating with the interior of said upper section at a point adjacent the inner surface of

said cap; and a passageway in said rod extending upwardly from said vent openings.

2. A deaerating device comprising: an upper cylindrical section; a lower cup-like section, the lower end of said cylindrical section and the upper end of said cup-like section having mating flanges for maintaining said sections in registration; a cap forming a closure for the upper end of said cylindrical section, said upper cylindrical section having an inlet duct arranged exteriorly of said section and discharging tangentially into the interior of said section, whereby liquid introduced through said inlet duct has a rapid whirling motion imparted thereto to remove the air therefrom, said inlet duct progressively decreasing in width and increasing in height in a circumferential direction from the entrance thereof to the point of discharge; said lower cup-like section having an axial core and a plurality of radial vanes extending outwardly from said core and merging with the inner surface of the side wall of said lower cuplike section, said radial vanes terminating short of the bottom of said lower cup-like section; a circular baffle plate resting upon said core and the upper edges of said radial vanes, said baffle plate being smaller in diameter than the internal diameter of said lower cup-like section, whereby to provide arcuate passageways for liquid between said upper and lower sections; a portion of the side wall of said lower cup-like section being thickened and projecting inwardly to a point underlying said circular baffle plate; an outlet opening extending through said thickened wall portion, whereby liquid is prevented from passing directly from said upper cylindrical section to said outlet opening; a rod extending through said cap and having a reduced end extending through said circular baffle plate and threaded into said axial core of said lower section, the upper end of said rod projecting through said cap member and being externally threaded; a nut threaded upon said projecting end of said rod and clamping said upper and lower sections and said cap member together, a washer secured to said rod at a point spaced below said cap member; a plurality of vent openings in said rod communicating with the interior of said upper section at a point between the inner surface of said cap and said washer, and a passageway in said rod extending from said vent openings to the upper end of said rod.

3. A deaerating device, comprising: a generally cylindrical housing including a side wall and top and bottom walls, said side wall having an inlet duct at its upper end arranged to discharge tangentially interiorly thereof, whereby liquid introduced through said inlet duct has a rapid whirling motion imparted thereto to remove the air therefrom; baffle means in the lower portion of said housing including a series of vanes extending inwardly from the inner surface of said side wall, said vanes terminating short of said bottom wall, a horizontal baffle supported by said vanes, and a pad on said side wall in one of the spaces between adjacent vanes extending from vane to vane and underlying said horizontal baffle, said horizontal baffle being spaced from the inner surface of said side wall to provide passageways for liquid communicating with the remaining spaces between said radial vanes, said cylindrical housing having an outlet opening for deaerated liquid communicating with said one space; and vent means for the discharge of the air separated from said deaerated liquid.

4. A deaerating device, comprising: an elong-

gated cylindrical housing having a side wall and top and bottom walls, said housing having an inlet duct adjacent the upper end thereof arranged to discharge liquid tangentially into the interior thereof, whereby liquid introduced through said inlet duct has a rapid whirling motion imparted thereto to centrifugally separate the air therefrom; horizontal baffle means in the lower portion of said housing arranged to restrict flow of liquid therethrough; and vertical baffle means in said housing below said horizontal baffle means arranged to convert whirling movement of all of the liquid introduced into said housing into downward substantially vertical movement, said housing having a constantly open outlet at the lower end thereof for deaerated liquid, said outlet constituting the sole means of egress for said deaerated liquid, said housing having a restricted air vent at the upper end thereof for restricting the discharge of air separated from said liquid to create a back pressure for aiding in producing an air vortex of a desired depth in said housing above said horizontal baffle means, said horizontal and vertical baffle means retarding liquid flow and operating with said restricted air vent to aid in maintaining said air vortex in said housing.

5. A deaerating device as defined in claim 4, including a splash plate fixedly mounted adjacent the air vent for preventing liquid from splashing into said air vent.

6. A deaerating device, comprising: elongated cylindrical housing means having a side wall and top and bottom walls, said housing having an inlet duct adjacent its upper end arranged to discharge liquid tangentially into the interior thereof, whereby liquid introduced through said inlet duct has a rapid whirling motion imparted thereto to centrifugally separate air therefrom, said housing having a plurality of radial vanes in the lower portion thereof extending inwardly from said side wall for interrupting whirling movement of said liquid and causing said liquid to move vertically downward, said radial vanes having lower ends terminating close to said bottom wall; a circular baffle plate resting horizontally upon the upper ends of said radial vanes, said baffle plate being slightly smaller in diameter than the internal diameter of said housing, whereby to provide arcuate passageways for restricting liquid flow past said baffle plate to the spaces between the vanes therebelow, said housing having a constantly open outlet in said side wall for deaerated liquid disposed below said baffle plate but above the lower ends of said radial vanes, said outlet constituting the sole means of egress for deaerated liquid; and restricted air vent means at the top of said housing cooperable with said baffle means for aiding in maintaining an air vortex of a desired depth in said housing above said baffle plate.

7. A deaerating device, comprising: an upper cylindrical section; a lower cup-like section separable from said upper cylindrical section and having a bottom wall and a cylindrical side wall axially aligned with said upper cylindrical section; a cap forming a closure for the upper end of said cylindrical section, said upper cylindrical section having an inlet duct arranged to discharge liquid tangentially into the interior of said section, whereby liquid introduced through said inlet duct has a rapid whirling motion imparted thereto to centrifugally separate the air therefrom, said lower cup-like section having an axial core extending upwardly from said bottom wall and a plurality of radial vanes extending outwardly

75

from said core and merging with the inner surface of the side wall of said lower cup-like section, said radial vanes having the lower ends thereof spaced from said bottom wall of said lower cup-like section; horizontal baffle means above said radial vanes arranged to provide passageways of limited area to restrict liquid flow between said upper and lower sections; a constantly open outlet for deaerated liquid in said lower section and constituting the sole means of egress for deaerated liquid; means securing said cap and upper and lower sections in assembled relation; and restricted air vent means cooperable with said baffle means and vanes for aiding in maintaining an air vortex of a desired depth in said upper section above said horizontal baffle means.

8. A deaerating device, comprising: an upper cylindrical section; a lower cup-like section having a bottom wall and a side wall aligned with said upper cylindrical section; a cap forming a closure for the upper end of said cylindrical section, said upper cylindrical section having an inlet duct for discharging liquid tangentially into the interior thereof, whereby liquid introduced through said inlet duct has a rapid whirling motion imparted thereto to remove the air therefrom, said lower cup-like section having an axial core and a plurality of radial vanes extending outwardly from said core and merging with the inner surface of the side wall of said lower cup-like section, said radial vanes terminating short of the bottom of said lower cup-like section; a removable circular baffle plate resting horizontally upon said core and the upper edges of said radial vanes, said baffle plate being slightly smaller in diameter than the internal diameter of said lower cup-like section, whereby to provide arcuate passageways for restricting liquid flow between said upper and lower sections, said lower cup-like section having a constantly open outlet for liquid below said baffle plate; a rod extending through said cap having its lower end threaded into said axial core of said lower section, the upper end of said rod projecting through said cap member and being externally threaded; means on said projecting end of said rod clamping said upper and lower sections and said cap member together; and restricted vent means for venting separated air from said upper section to the atmosphere.

9. A deaerating device comprising an upper cylindrical section; a lower cup-like section having a bottom wall and a side wall aligned with said upper cylindrical section; a cap forming a closure for the upper end of said cylindrical section, said upper cylindrical section having an inlet duct for discharging liquid tangentially into the interior thereof, whereby liquid introduced through

said inlet duct has a rapid whirling motion imparted thereto to remove the air therefrom, said lower cup-like section having an axial core and a plurality of radial vanes extending outwardly from said core and merging with the inner surface of the side wall of said lower cup-like section, said radial vanes terminating short of the bottom of said lower cup-like section; a removable circular baffle plate resting upon said core and the upper edges of said radial vanes, said baffle plate being slightly smaller in diameter than the internal diameter of said lower cup-like section, whereby to provide arcuate passageways for restricting liquid flow between said upper and lower sections, said lower cup-like section having a constantly open outlet for liquid below said baffle plate; a rod extending through said cap having its lower end threaded into said axial core of said lower section, the upper end of said rod projecting through said cap member and being externally threaded; and means on said projecting end of said rod clamping said upper and lower sections and said cap member together, said rod having a plurality of restricted vent openings communicating with the interior of said upper section at a point adjacent the inner surface of said cap and also having a passageway extending upwardly from said vent openings to the exterior of said cap member.

10. A deaerating device as defined in claim 9, wherein a splash plate is mounted upon the rod adjacent the cap but below the vent openings.
